[57] CLAIM

The ornamental design for a container for lint-removing adhesive strips, as shown and described.

DESCRIPTION

FIG. 1 is a perspective view of a container for lint removing adhesive strips showing my new design;

FIG. 2 is a left side elevation thereof;

FIG. 3 is a front elevation thereof, the rear side elevation being a mirror image;

FIG. 4 is a right side elevation thereof;

FIG. 5 is a top plan view thereof; and

FIG. 6 is a bottom plan view thereof.

FIG. 1.

FIG. 2.

FIG. 3.

FIG. 4.

FIG. 5.

FIG. 6.

UNITED STATES PATENT AND TRADEMARK OFFICE
CERTIFICATE OF CORRECTION

PATENT NO. : Des. 305,988
DATED : February 13, 1990
INVENTOR(S) : VIRGIL R. SWOPE, JR.

It is certified that error appears in the above-identified patent and that said Letters Patent is hereby corrected as shown below:

TITLE PAGE:

The correct name of the inventor is: VIRGIL R. SWOPE, JR.

Signed and Sealed this
Seventh Day of May, 1991

Attest:

HARRY F. MANBECK, JR.

Attesting Officer

Commissioner of Patents and Trademarks
